LIGHTING FIXTURE

Dillard M. Smith, Beverly Hills, and Jan Jaspers Fayer,
Palos Verdes Peninsula, Calif., assignors to Eagle Man-
ufacturing Co., Industry, Calif., a corporation of
California

Filed Sept. 15, 1965, Ser. No. 87,006

Term of patent 14 years

(Cl. D48—16)

FIG. 1 is a side elevational view of a lighting fixture showing our new design;

FIG. 2 is a top plan view thereof;

FIG. 3 is a view similar to FIG. 1 but showing another embodiment of our new design; and

FIG. 4 is a plan view of the lighting fixture of FIG. 3.

We claim:

The ornamental design for a lighting fixture, substantially as shown.
